UNITED STATES PATENT OFFICE

LEONARD CLAYTON RIDGE, OF TORONTO, ONTARIO, CANADA

FILING DEVICE

Application filed August 2, 1926. Serial No. 126,580.

The invention relates to improvements in filing devices as described in the present specification and shown in the accompanying drawings that form a part of the same.

5 The invention relates to devices for the filing of office records, card indexes, papers, folders, correspondence and any other matter which is now preserved in drawers, cabinets, or desk drawers, commonly called vertical files.

10 The primary object of the invention is to provide a simple means of maintaining the contents of a filing drawer in a vertical position, without the necessity of compressing 15 the contents by means of a compressor or follower block.

A further object of the invention is to provide such an alternative means as can be constructed entirely of metal.

20 Numerous devices with the object of providing such an alternative have been produced from time to time, most of which necessitate the provision of transverse bars, or supports to the sectionalizing compartments, such supports being movable longitudinally of the compartments on trackways, rails or the like.

25 Difficulties in filing have arisen owing to the sectionalizing compartments being capable of excessively wide opening longitudinally, limited only by the full depth of the sectionalizing compartments.

The present invention aims to provide a series of compartments with adequate supports to maintain the filing matter in a vertical position and at the same time obviate the necessity of transverse bars or trackways, and also by the use of flexible means securing together the various sectionalizing compartments at their bottoms, to limit the spreading of such compartments in relation to each other.

35 The invention also consists in the novel features of construction, arrangements and combinations more particularly explained in the following specification.

40 In the drawings Figure 1 is a longitudinal sectional view through a cabinet with the compartments in side elevation, said com-

partments, or pockets, being in their non-distended condition.

Figure 2 is an irregular cross section taken on the line 2—2 of Figure 1.

Figure 3 is a view of the under side of a 55 portion of the device shown in Figure 1, removed from the container.

Figure 4 is a side elevation of the device shown in Figure 3, showing a modified form 60 of flexible connection.

Figure 5 is a cross sectional view taken on the line 5—5 of Figure 4.

Like numerals of reference indicate corresponding parts in the various figures.

Referring to the drawings, 1 is the file 65 drawer, or container, which may be of any desired design.

The filing compartments 2 are preferably formed by folding a single strip of inflexible material, preferably thin sheet metal, 70 to provide vertical V-shaped pockets positioned one behind the other and adapted to rest loosely on the bottom of the container and not being secured to said container at any point, this method of construction providing for a rigid connection between the adjacent walls of each compartment at the top but permitting of movement of the bottoms of said compartments in relation to each other longitudinally of the container, 75 80 which movement is essential to the efficiency of the device.

The side walls of each of the compartments 2 are scored, or otherwise weakened, at equal distances from, and parallel to, 85 the bottom fold 3, as at 4, to permit of the expansion of the compartments to meet requirements due to increase in the quantity of filed matter.

In order to preserve the proper vertical 90 relationship between the compartments and at the same time to permit of the necessary elasticity a flexible connection is provided between adjacent compartments at the bottoms thereof which effectually limits the 95 spread of the bottoms of the compartments in relation to each other and prevents the compartments from assuming a leaning position.

The particular method or design of con- 100

struction of this flexible connection does not constitute the essential feature of the present invention and this connection may take the form of two, or more, strips 5 of tape, or other like material, extended longitudinally of the device along the bottom thereof at each side and connected to the respective compartments at regular intervals along its surface by means of fasteners 6 projected therethrough and through the transverse centres of the bottoms of said compartments, or, a single element may be employed, such as a chain 7 carrying transversely arranged bars 8 at regular intervals therealong adapted to be projected through openings in the bottoms of said compartments, in which case it is preferable to employ but one connecting element and to position same in the transverse centre of the container so that the slack portions of said chain may rest in the channel 9 with which such cabinets are provided.

In the use of this invention the matter to be filed is placed in the desired compartment, the bottom of which, as the contents of the compartment increase in transverse proportions, expands to meet the requirements owing to the walls thereof being scored parallel with the bottom fold thereof, and while the lower portions of the compartments are free to move towards and away from each other the distance necessary in the operation of the device this movement is limited by the flexible connections between the bottoms of the compartments,

It will thus be apparent that this construction provides a filing device which can be used conveniently on a desk, or elsewhere, without the employment of an enclosing cabinet, as the compartments being constructed of inflexible material will hold the contents in an upright condition and the flexible connections will effectually prevent the collapse of the compartments.

What I claim is:—

1. A filing device including a container, a plurality of parallel transverse pockets arranged in the container in connected relation, each pocket being open at its upper end and closed at its lower end, the upper ends of the respective pockets being connected one to the other, the closed lower ends of the pockets being spaced apart, and means connecting the lower closed ends of the pockets to maintain the pockets in substantially vertical position in the container without interfering with the normal spread of the pockets under the introduction of material therein.

2. A filing device including a container, a plurality of pockets arranged in the container, each pocket being open at its upper end and closed at its lower end, the adjacent walls of successive pockets being connected at their upper ends to maintain a sub-

stantially rigid pocket formation at the upper end, and a flexible element connecting the lower ends of the pockets to maintain said pockets substantially vertically in the container without interfering with the application of material within the pockets.

Signed at Toronto, Ont., this 29th day of July, 1926.
